DESIGN FOR A LAMP

Nels A. Nelson, Frankfort, Mich.

Application July 19, 1938, Serial No. 78,587

Term of patent 3½ years

Be it known that I, Nels A. Nelson, a citizen of the United States of America, residing at Frankfort, county of Benzie, and State of Michigan, have invented a new, original, and ornamental Design for Lamps, of which the following is a specification, reference being had to the accompanying drawing, wherein:

It is to be understood the opposite side of the design is substantially the same in appearance as the side shown, in the accompanying drawing.

The figure is a perspective view of a lamp, showing my new design.

I claim:

The ornamental design for a lamp, as shown and described.

NELS A. NELSON.
